IMPROVEMENT IN COOKING-STOVES.

FREDERICK M. BAKER, OF SOUTH READING, MASSACHUSETTS.

Letters Patent No. 60,118, dated December 4, 1866; antedated November 22, 1866.

SPECIFICATION.

TO ALL PERSONS TO WHOM THESE PRESENTS SHALL COME:

Be it known that I, FREDERICK M. BAKER, of South Reading, in the county of Middlesex, and State of Massachusetts, have invented a new and useful Improvement in Cooking-Stoves, and do hereby declare the same to be fully described in the following specification and represented in the accompanying drawing, which denotes a longitudinal section of a cooking-stove provided with my invention.

My present improvement has reference to a stove analogous to that invented by me, and for which Letters Patent No. 50,765 were granted to Charles Jordan, my assignee, on the thirty-first day of October, A. D. 1865.

The drawing represents an ordinary cooking-stove provided with an oven, A, and with flues B, B¹, B², and C, for leading the smoke from the fire-place, P, against the top, the back plate, and the bottom of the said oven. An auxiliary oven, G, is disposed in rear of the main oven A, and an upright flue, F, placed between the flue B¹ and the said auxiliary oven, G. This flue F opens out of the flue C by an opening, b², and into the space B² by an opening, a², there being a damper, D², applied so as to be capable of closing either of the said openings. Another damper, D, is arranged at the upper parts of the flues B F, and so applied that when turned down into a horizontal position it shall close both flues B¹ F, but when turned up into a vertical position it shall cut off communication between the flue B and a flue, I, leading over and against the top of the auxiliary oven, G, and open communication between the flues B and B¹ and the flues F and I. There is a flue, m, leading from the flue B², directly underneath and against the oven G, and up and along its back to the flue I; and there is also a flue, H, leading from the flue C along underneath and upward against the flue m, and to the escape-flue, b. A damper, D³, is arranged at the heads of the flues m and H, and so that when such damper is turned into a horizontal position it shall close the upper ends of both the flues m and H. When inclined or raised, the said damper should cut off communication between the flue I and the escape-flue b, so as to direct the smoke from the flue I into the flue m, from whence it may be made to flow directly into the flue H, or first through the flue B² and into the flue C, and finally escape into the pipe b. One or more apertures for the reception of boilers may be made in the top plate of the stove, and over either or both of the ovens.

With my arrangement of flues and dampers the smoke may be caused to go around the main oven without contact with the auxiliary oven, or it may be caused to pass partly around each of the ovens, or it may be made to pass over the main oven, thence into the flue I, thence down and through the flue m, and thence through the flue H. In fact, the arrangement is such as will permit various advantageous applications of the smoke to either or both of the ovens, in order to use either or both of them for baking or simply for heating or various purposes.

I do not claim a stove made with two ovens, but what I do claim is, the combination as well as the arrangement of the flues m and H, the dampers D D², and D³, and openings a², b², with the auxiliary oven G, its flue F, and the main oven and its flues B, B¹, B², and C, the whole being substantially as hereinbefore specified.

F. M. BAKER.
